[57] CLAIM

The ornamental design heel plate for a boot or shoe, as shown and described.

DESCRIPTION

FIG. 1 is a perspective view of a heel plate for a boot or shoe showing my new design;

FIG. 2 is a front elevational view thereof;

FIG. 3 is a rear elevational view thereof;

FIG. 4 is a side elevational view, the opposite side being a mirror image thereof;

FIG. 5 is a top plan view thereof; and,

FIG. 6 is a bottom plan view thereof.

The broken line showing of a portion of a boot in FIG. 1 is for illustrative purposes only and forms no part of the claimed design.

FIG. 3

FIG. 4
